METHOD AND APPARATUS FOR TREATING STRINGS OR STRANDS

Application filed July 31, 1928, Serial No. 296,588, and in Great Britain August 4, 1927.

This invention relates to a new or improved process for treating strings or strands composed of or containing substances that are susceptible to a change of the nature of vulcanization, such substances being vegetable resins.

According to this invention, the process consists in principle, in subjecting the strings or strands to heat in the manner generally referred to as vulcanizing, the heat being obtained by forcing steam (or other fluid) into a suitable apparatus while the pressure thereby developed is advantageously utilized to actuate devices which maintain a continual longitudinal pull upon the strings, the tension so imparted comprising an essential feature of the treatment.

Another object is to construct such apparatus so that the strings or strands are continuously tensioned, irrespective of the degree to which they yield longitudinally during the treatment.

A further object is in constructing such apparatus so that the tension imparted to the strings or strands is proportioned to the heat to which they are subjected.

The strings or strands to which this invention relates are generally referred to in the trade as gut strings, not so much on account of their constituents, but more on account of their application. Such strings have a marked application for stringing tennis rackets. The invention is particularly applicable to strings composed at least in part of either rubber, gutta percha, or similar vegetable resins.

In order that this invention may be clearly understood, reference should be made to the accompanying drawings wherein—

Fig. 1 is a part sectional side elevation of the apparatus;

Fig. 2 is a plan view of Fig. 1;

Fig. 3 is a cross-sectional view on line 3—3 of Fig. 1;

Fig. 4 is a part sectional view on an enlarged scale of the yielding hook member;

Fig. 5 is an enlarged sectional view of the juncture between the pipe and the aperture within the container.

In a convenient embodiment of the appara-

tus according to the invention, we employ essentially a heating chamber 1 having a door or closure member 2 at one end, and being constructed to make a gas-tight juncture when closed.

Capable of entering the heating chamber is a frame or carriage member 3 for receiving thereon lengths of the strings or strands 4 to undergo the treatment.

The frame or carriage may be rectangular in shape and comprises two end members 5—6 which correspond with the shorter sides of the rectangle and two side members corresponding with the remaining longer sides of the rectangle. Any convenient construction of frame may be employed but a suitable one may be constructed partly of angle metal suitably struttied and jointed to be consistent with strength and durability.

Further, we prefer to mount the frame or carriage upon wheels 7 adapted to be received upon rails 8 which extend into the heating chamber in order to facilitate the easy manipulation of the frame when being placed into or removed from the heating chamber.

Provided upon the end members of the frame or carriage 3 and substantially in alignment with one another are hooks or other retaining devices 9—10 for receiving the ends of the gut or other strings or strands 4.

The hooks or other devices 9 at the one end of the frame or carriage may be of a rigid and unyielding nature, while the hooks 10 at the other end are of particular construction and constitute an important feature of the invention. Each of these latter hooks 10 comprises essentially a stem portion 11 having a hook at one end while on the other end is a piston 12 of suitable proportions. This piston is adapted to work within an elongated cylinder 13 which is secured in a suitable manner to a chest or other hollow member 14 at the end 6 of the frame.

Along the stem portion of this combined hook and piston member is a series of ratchet teeth 15 and coacting with those teeth is a gravity actuating pawl or detent 16 mounted upon a spindle 17 fixed in relation to the cylinder.

In order to support the cylinder 13 its extended end 18 to which the pawl 16 is secured, is received within an aperture in a plate member 19 upstanding from and mounted upon the frame member.

Further, to ensure the ease of movement of the stem along the cylinder, it may be adapted to rest upon a roller or other member 20 mounted at 21 at the open end of the extension 17. The function of this combined hook and piston is as follows:—

The piston is forced along the cylinder in the direction towards the end of the frame or carriage to which it is secured in consequence of pressure acting upon it and as the piston traverses the cylinder, it draws the stem and hook with it causing the distance between the two hooks to increase.

Another feature of importance in constructing this apparatus according to this invention refers to the cylinder members. In order that the pistons may traverse along the cylinders it is necessary to remove and insulate the pressure from their inoperative faces.

To accomplish this we cause the cylinders 13 to communicate with a hollow chamber 14 mounted at the end 6 of the frame or carriage.

Connected to this hollow chamber 14 is an extending pipe member 22 which is capable of passing through an aperture 23 in the wall of the heating chamber thereby placing this hollow chamber in direct communication with the atmosphere. Suitable provision is made to ensure that the joint between the extending pipe member and the aperture in the heating chamber is steam or gas-tight and in a construction adopted we have provided a somewhat conical shaped facing 24 near the end of the extending pipe member 22 and which is adapted to co-operate with a corresponding conical seating 25 around the aperture within the heating chamber. The corresponding seating 25 is provided within a ring 26 and is mounted to permit of radial displacement, so that it will readily align itself with the pipe member, the ring further contacting with a packing member 27 provided within the facing of one of the members of its housing.

In operation, the extending pipe member 22 is passed through the aperture in the heating chamber until the respective facings and seatings engage, the pressure within the chamber maintains them in engagement, but in order to ensure of their more intimate engagement we apply a nut-like member 28 upon a screw threaded portion 29 provided at the remote end 30 of the extending member 22.

If desired a buffer or extensible member 31 acted upon by a spring 32 may be provided at the end 5 of the frame 3.

In operation, the strings or strands are first attached to the hooks or other retaining

members 9—10. The frame or carriage is then placed into the heating chamber, after which the door or closure member 2 is tightly secured and the nut-like member 28 placed in position on the extended pipe.

We now cause heat and pressure to develop within the heating chamber by forcing thereinto steam, or other fluid, through an aperture as 33 in Fig. 1 or by any other means.

The heat developed by the steam or other heated fluid acts upon the strings of rubber or gutta percha and similar vegetable resins in a manner generally known as vulcanizing causing the characteristics of the strings or strands to somewhat alter, while the pressure operates the tensioning devices, it being appreciated that a difference in pressure or heat occasions different results. Thus it is clear that the strings are simultaneously vulcanized under tension and pressure.

The term vulcanizing, hereinbefore mentioned, refers generally to the treatment which may be applied to any types of strings and strands the characters of which alter when subjected to heat and does not solely refer to strings or strands wherein rubber is one of the components as the term may suggest.

When the required pressure and heat have been produced within the heating chamber, it will be found that the pistons have been forced into the cylinders and retained against return movement by the gravity actuated pawls engaging with the ratchet teeth on the stems of the combined pistons and hooks, reference should be made to Fig. 2, where one of the hooks 10 is shown in the position it assumes at the commencement of the treatment, while the other hook 10 is shown with the pressure acting upon it, and imposing a tension upon the strings as at the finish of the treatment. Upon the treatment having been completed, the strings or strands can be removed from the apparatus by releasing the pawl from engagement with the ratchet teeth.

From the foregoing description, it will be observed that the gut strings or the like have been described as being treated in a single length and having each of their ends attached to a retaining device, but we may if desired treat them in any other manner, such for instance as in doubled lengths as shown in Fig. 2, where we provide two retaining hooks at the one end, to one combined piston and hook on the other, the string being folded upon itself and looped over the combined piston hook.

According to one of the features of the treatment according to this invention, it has been found desirable to tension the strings or strands relative or proportional to the heat of the fluid, so that as the heat varies either to greater or lesser extent, there is a pro rata variation in the pressure within the chamber.

This condition is effected in one instance by

the characteristics of the fluid, as for instance with steam, alternatively, and when other fluid is used for instance heated air, a thermionic or other valve may be used to control the admittance of the fluid according to its heat, and thereby govern the pressure within the chamber.

Also it will readily be appreciated that the frame or carriage may be constructed to receive any number of strings, see Fig. 3, where a number of apertures 34 are shown for receiving the hooks 9. According to the foregoing description, the hooks 9 are described as being of a rigid and unyielding nature, but it should be understood that the rigidity is required only in the longitudinal direction, but for convenience the apertures 34 are of keyhole formation, permitting the hooks of lateral displacement to allow them to be readily connected to or disconnected from the frame, the enlarged part 35 of the hooks retaining the hooks in the narrow part of the aperture 34.

It will be appreciated that constructional details may be modified without departing from the objects of the invention.

The strings or strands referred to usually comprise a stranded core coated with gutta percha or similar vegetable resins. Such stranded core may be of the usual string-like fiber or in some cases it is made of one or more metallic wire strands.

Having now particularly described and ascertained the nature of the said invention, and in what manner the same is to be performed, we declare that what we claim is:—

1. The method of treating strings of vulcanizable material of the kind described, which comprises subjecting said strings to fluid under pressure at a vulcanizing temperature and imposing a longitudinal tension upon said strings, said tension being a function of the pressure of said fluid.

2. The method of treating strings of vulcanizable material of the type described, which comprises subjecting said strings to fluid under pressure at a vulcanizing temperature and imposing a longitudinal tension upon said strings, said tension being directly proportional to the pressure of said fluid.

3. The method of treating strings of vulcanizable material of the type described, which comprises subjecting said strings to a fluid under pressure at a vulcanizing temperature, and continuously and constantly tensioning said strings during vulcanization irrespective of the length of stretch occurring in them, and with a tension proportional to the pressure of said fluid.

4. Apparatus for treating strings of the type described, which comprises a fluid-tight chamber, a frame having retaining devices for receiving and carrying said strings, said retaining devices being movable to and from each other, and means for moving said retain-

ing devices to increase the distance between them and to impose a longitudinal tension upon strings supported between said devices.

5. Apparatus of the type described, which comprises a pair of retaining devices for supporting strings extending there between and secured thereto, said devices being movable to increasing distances from each other, fluid pressure actuated means to move said devices from each other, and means for supplying heated fluid under pressure to strings supported between said retaining devices.

6. Apparatus of the type described, which comprises a pair of retaining devices for supporting strings extending there between and attached thereto, means for separating said devices from each other under pressure to tension said strings, means for retaining said devices in separated positions against the tensioning action of said strings, and means for supplying fluid under pressure to said strings.

7. Apparatus of the type described, which comprises a frame, string supporting and retaining devices relatively movable on said frame to impose a longitudinal tension upon strings supported between said devices, means for moving said devices from each other, means for preventing the return movement of said receiving devices, and means for supplying fluid under pressure to said strings.

8. Apparatus of the type described, which comprises relatively movable string retaining devices, a cylinder, a piston in said cylinder and connected to one of said movable devices, means for imparting a difference of pressure to opposite sides of said piston to move said devices apart relatively to each other, and means for supplying fluid under pressure to said strings.

9. Apparatus of the type described, which comprises relatively movable string retaining devices, a cylinder, a piston in said cylinder and connected to one of said movable devices, means for imparting a difference of pressure to opposite sides of said piston to move said devices apart relatively to each other, a ratchet and pawl means for preventing return movement of said movable retaining means, and means for supplying fluid under pressure to said strings.

10. Apparatus according to claim 8, wherein the cylinder communicates with the atmosphere.

11. Apparatus of the type described, which comprises a fluid pressure chamber, means in fixed position in said chamber to engage a string to be stretched, movable means in said chamber for engaging said string, a cylinder in said chamber communicating with the atmosphere, and a piston in said cylinder and connected to said movable string retaining means to stretch the latter as said piston moves under the difference of pressure be-

tween the atmosphere and the interior of said chamber, and means for supplying heated fluid under pressure to said chamber.

12. Apparatus for treating strings of the kind specified, comprising a fluid tight chamber with fluid admitting orifice, and with a displaceable end, and having rails at its floor in combination with a frame or carriage mounted on said rails and capable of being moved into or from said chamber, the said frame or carriage having string retaining devices some of which can move under the pressure of the fluid to impose a longitudinal tension upon said strings, wherein the cylinders for receiving the moving devices communicate with the atmosphere through a hollow member extending through the wall of the container and a fluid tight juncture between said hollow extending member and said container.

13. In apparatus according to claim 12, a fluid tight juncture comprising a male member having a conically shaped surface received within a correspondingly shaped floating female member, substantially as described.

14. In apparatus according to claim 12, a fluid tight juncture comprising a male member having a conically shaped surface received within a correspondingly shaped female member, the union between them being occasioned by the pressure of the fluid within the container.

15. In apparatus according to claim 12, wherein the union between the male and female members is assured by a nut substantially as described.

16. In apparatus according to claim 12, wherein retaining devices are displaceable laterally and received within a keyhole shaped aperture substantially as described.

In witness whereof, we have hereunto signed our names.

HARRY WILLSHAW.
